(57) CLAIM

The ornamental design for a chair, as shown and described.

DESCRIPTION

FIG. 1 is a front perspective view of a chair showing my new furniture design;

FIG. 2 is a front view of the chair shown in FIG. 1;

FIG. 3 is a back view of the chair shown in FIG. 1;

FIG. 4 is a side view of the chair shown in FIG. 1;

FIG. 5 is the other side view of the chair shown in FIG. 1

FIG. 6 is a top view of the chair shown in FIG. 1; and,

FIG. 7 is a bottom view of the chair shown in FIG. 1.

The broken line showing of the screws, seat mechanism, and bottom pole aperture shows unclaimed subject matter/is not part of the claimed design.

1 Claim, 6 Drawing Sheets

FIG. 1

FIG. 2

FIG. 3

FIG. 4

FIG. 5

FIG. 6
